REINFORCED CONSTRUCTION UNIT

Filed July 12, 1927

Fig. 2.

Inventor

J. T. Saltiel.

By *Ley & Lucy*, Attorney

UNITED STATES PATENT OFFICE.

JOHNATHON T. SALTIEL, OF GARY, INDIANA, ASSIGNOR TO JOHN A. TAMAN AND OSBORNE J. TAMAN, BOTH OF GARY, INDIANA.

REINFORCED CONSTRUCTION UNIT.

Application filed July 12, 1927. Serial No. 205,208.

This invention relates to a reenforced construction unit and one object of the invention is to provide a unit of this character formed of reenforced cement and having its reenforcing means embedded in the cement body of the unit or block to prevent it from cracking or breaking and to project portions of the reinforcements from the block so that they constitute anchors to be secured to a support or embedded in mortar constituting a backing or support for the block.

Another object of the invention is to so arrange the projecting portions of the reinforcements that, when the blocks or units are set in place, certain of the projecting end portions of the reinforcements may be conveniently attached to a beam or other support forming part of a building or other structure to which the units are to be applied and the remaining end portions of the reinforcements embedded in mortar forming a backing for the units.

Another object of the invention is to provide units which may be employed to construct a floor and may be very securely anchored to supporting beams constituting part of the frame of a building.

Another object of the invention is to provide units which may be employed to build a chimney or column and may be firmly held in proper relation to each other.

Another object of the invention is to prevent units placed one upon another from having movement relative to each other and thereby permit the units to be quickly set in place.

Another object of the invention is to so dispose reinforcements in the units that their end portions may project and constitute pins to be received in sockets formed in companion units and very securely retain the units in proper relation to each other.

The invention is illustrated in the accompanying drawings, wherein

Figure 1 is a perspective view of one of the reenforced construction units;

Fig. 2 is a longitudinal sectional view taken on the line 2-2 of Fig. 1;

Fig. 3 is a transverse sectional view taken through the construction unit taken on the line 3-3 of Fig. 1, and

Fig. 4 is a sectional view showing the man-

ner of securing construction units such as shown in Fig. 1 to the frame of a building.

The reenforced construction unit shown in Fig. 1 is indicated in general by the numeral 1 and includes a body portion formed of concrete, cement or other settable material. The block or unit is preferably oblong in shape although it may have any shape desired and is preferably so shaped that its outer portion is of an even length and width, whereas its inner portion tapers rearwardly. Therefore, when the units or blocks are employed to erect a wall, the mortar 2 provided between adjacent units may form very good keys, as shown in Fig. 4. A metal fabric 3 which may consist of expanded metal or interwoven wire is embedded in the body of the unit with its end portions extending from the body and adapted to be bent rearwardly so that it may be firmly secured to vertical beams or studs 4 forming part of a building frame. Staples or nails may be employed to secure the extending end portions of the fabric to wooden beams and if the beams are metal the fabric may be welded, riveted or secured thereto in any desired manner. It should also be noted that a portion of the mortar will pass through the meshes of the reinforcing fabric and assist to retain the blocks in proper position relative to each other when erecting a wall.

An auxiliary mesh reinforcement 5 has been shown in Figs. 1 and 2, and it will be understood that additional reinforcements of this type may be employed if so desired. Metal strips 6 which are preferably perforated extend longitudinally through the body with their end portions projecting therefrom and similar strips 7 extend transversely through the body with their ends projecting from the upper and lower edge faces thereof. The strips 6 are to be nailed, riveted or otherwise rigidly secured to supporting beams or studs 4 and the strips 7 may be either secured to supporting beams or may be merely bent rearwardly and embedded in mortar between the wall and frame of a building where they will constitute anchors to assist in holding the blocks in their proper positions. Additional strips 8 extend longitudinally in the block and have their end portions bent outwardly, as shown at 9, to provide anchors which may be secured to beams of a building

frame if convenient or embedded in mortar, as previously set forth. By having the block provided with a number of reenforcing strips having their end portions projecting from the ends, sides and rear face of the block it will always be possible to secure some of the projecting end portions to supporting beams and the remaining end portions will be merely embedded in mortar. Therefore, when a wall is constructed of these units all of the units may be firmly anchored to a frame of a building and securely braced and anchored in mortar so that they will be retained in proper relation to each other.

Having thus described the invention, I claim:

1. A reenforced construction unit comprising a body of set material, and reenforcing strips embedded in said body and having end portions projecting from the body and constituting anchors, certain of said strips hav-

ing their end portions projecting from edge faces of the body and the remaining strips having their end portions projecting from the rear face of the body intermediate its side and ends. 25

2. A reenforced construction unit comprising a body of set material, and reenforcing strips embedded in said body and having end portions projecting from the body and constituting anchors, certain of said strips extending transversely in the body with their end portions projecting from the side edge faces thereof and the remaining strips extending longitudinally in the body and certain of their end portions projecting from the body adjacent its ends and the remaining end portions projecting from the rear face of the body intermediate its sides and ends. 30 35

In testimony whereof I affix my signature.

JOHNATHEON T. SALTIEL. [L.S.]
